PENCIL OR SIMILAR ARTICLE

Garfield L. Beckstrom, Chicago, Ill., assignor to Autopoint Company, Chicago, Ill., a corporation of Illinois

Application November 5, 1951, Serial No. 17,293

Term of patent 14 years

(Cl. D74—24)

To all whom it may concern:

Be it known that I, Garfield L. Beckstrom, a citizen of the United States, residing at Chicago, in the county of Cook and State of Illinois, have invented a new, original, and ornamental Design for a Pencil or Similar Article, of which the following is a specification, reference being had to the accompanying drawing, forming a part thereof.

In the drawing:

Fig. 1 is an elevational view of a pencil embodying my new design;

Fig. 2 is an enlarged longitudinal cross section of the cap portion;

Fig. 3 is a bottom plan view of the cap portion; and

Fig. 4 is a fragmentary view of the pencil illustrated in a horizontal position.

The dominant features of the design are shown in full lines.

I claim:

The ornamental design for a pencil or similar article, substantially as shown and described.

GARFIELD L. BECKSTROM.
